(57) **CLAIM**

The ornamental design for a body sculpting massager, as shown and described.

DESCRIPTION

FIG. 1 is a perspective view of the body sculpting massager showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the figures are for the purpose of illustrating portions of the body sculpting massager, which form no part of the claimed design.
